UNITED STATES PATENT OFFICE.

JOSEPH HENRY McEVOY, JR., OF HOUSTON, TEXAS.

STRAINER FOR WELLS.

Application filed September 28, 1925. Serial No. 59,063.

My invention relates to a well strainer for filtering the impurities from liquid coming from the producing formation into the well.

It is an object of the invention to provide a compound filtering means, in a button type strainer, which will most efficiently limit the entrance of foreign particles, such as sand, to the interior of the pipe. It is desired to provide a plurality of screening surfaces 10 with a space between them, in which foreign material may gather to assist in the filtering operation.

In the drawing, I have illustrated my invention as applied to one form of button strainer. Fig. 1 shows a top plan view of a broken pipe section with the invention applied thereto. Fig. 2 is a longitudinal section of a pipe with my improvement therein. Fig. 3 is a plan view similar to Fig. 1 but illustrating a slightly different arrangement. Fig. 4 is a longitudinal section of the Fig. 3 embodiment. Like numerals refer to like parts in all the views.

The form of button or plug shown in the drawing and the method of securing the same in position in the pipe are believed to be old. The pipe 1 is of the usual heavy construction employed in deep oil wells. A circular opening 2 is bored in the said pipe for each filtering inlet and it is understood that the number of openings may be regulated as desired.

The openings 2 are reamed to enlarge the same from the outer side of the pipe, the reamed portion 3 providing a seat or shoulder 4 to receive the filtering buttons.

My invention consists in the seating, in the reamed openings, of a plurality of buttons, one on top of the other. The buttons are preferably made of discs of metal, such as brass or steel, one side of which is cupped somewhat, having a marginal rim 5. The wall 6 between this cupped portion and the other side is provided with a plurality of parallel slots 7, the walls of which are parallel adjacent the outer face, but diverge rapidly toward the cupped side to provide inner troughs 8. The fluid entering through the slots 7 finds a free passage through the widening troughs 8 to the interior of the pipe. The ordinary difficulty with this type

of strainer, where one button is used in each opening, is that the fine sand may enter and gradually wear away the walls of the slots, thus impairing the original effectiveness of 55 the screen.

I, therefore, employ two of these buttons, one set on top of the other so as to provide an open space 9 between them. In said space 9, the current of flowing oil is slower 60 than through the narrow slots of the buttons and the grains of sand may therefore settle out to some extent before the fluid passes through the inner strainer plug. The sand 65 may gradually accumulate to fill the space 9 and act as a further filtering medium in combination with the two buttons.

The slots of the two buttons may be set at right angles to each other, as in Figs. 1 and 2, or they may be set parallel as shown in Figs. 3 and 4. The Fig. 1 embodiment is somewhat preferred because it allows a more 70 devious passage for the liquid, thus assisting in the settling out of the sand that passes the outer plug. When the plugs have been seated in the reamed opening, the edge 10 of the said opening may be upset to hold the buttons in position.

The advantages of my invention lie in the use of a plurality of buttons of the type described, in such manner that they may together form a compound filter employing sand as a portion of the screening medium.

Having thus described my invention, what I claim as new and desire to protect by Letters Patent is:

1. A well strainer comprising a pipe having inlet openings therein, a plurality of strainer plugs in each of said openings, said plugs comprising circular slotted discs fitting said openings, one face of each disc being cupped, said cupped faces being directed inwardly of the pipe whereby a space is provided between said discs for the accumulation of sand, in the manner described.

2. A well strainer comprising a pipe having inlet openings therein, a reamed seat in each opening, a plurality of strainer plugs in each opening fitting in said seat, each plug comprising a disc cupped on one side and having strainer slots in the outer wall, the cupped faces being directed inwardly of

the pipe and providing a space between adjacent plugs, said slots widening inwardly in the manner described.

3. A well strainer comprising a pipe having inlet openings therein, an inner shoulder in each opening, a plurality of strainer plugs of the same external diameter secured in each opening outside said shoulder, each plug be-

ing formed of a circular disc cupped on one side and slotted to provide strainer passages, 10 the slots on one plug being set at right angles to the slots on the next adjacent plug.

In testimony whereof I hereunto affix my signature this 23d day of September, A. D. 1925.

JOSEPH HENRY McEVOY, JR.
